(57) **CLAIM**

The ornamental design for an automobile tire, as shown and described.

DESCRIPTION

FIG. 1 is a perspective view of an automobile tire showing our design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a partially enlarged view of a portion defined by lines 8-8 shown in FIG. 1;

FIG. 9 is a partially enlarged view of a portion defined by lines 9-9 shown in FIG. 2;

FIG. 10 is a cross sectional view of a portion defined by lines 10-10 shown in FIG. 9; and,

FIG. 11 is a partially enlarged view of a portion defined by lines 11-11 shown in FIG. 2.

The dash-dot-dash style broken lines define the bounds of the claimed design and form no part thereof. The broken lines showing represent portions of the tire which form no part of the claimed design.

1 Claim, 11 Drawing Sheets
